RECESSED SOAP DISPENSER UNIT

William S. Louchheim, Beverly Hills, and Donald A. Gerd, Manhattan Beach, Calif., assignors to Bobrick Manufacturing Corporation, Los Angeles, Calif., a corporation of Delaware

Filed Aug. 1, 1960, Ser. No. 61,591

Term of patent 14 years

(Cl. D4—3)

FIG. 1.

FIG. 2.

FIG. 3.

FIG. 4.

FIG. 5.

FIG. 6.

FIG. 1 is a front perspective view of a recessed soap dispenser unit showing our new design;

FIG. 2 is a rear perspective view thereof;

FIG. 3 is a front perspective view of a second embodiment of our design;

FIG. 4 is a rear perspective view thereof;

FIG. 5 is a front perspective view of a third embodiment of our design; and

FIG. 6 is a rear perspective view thereof.

We claim:

The ornamental design for a recessed soap dispenser unit, as shown and described.
